UNITED STATES PATENT OFFICE.

WILLIAM A. GIBSON, OF DETROIT, MICHIGAN.

DISK WHEEL.

Application filed May 27, 1922. Serial No. 564,084.

To all whom it may concern:

Be it known that I, WILLIAM A. GIBSON, a citizen of the United States, residing at Detroit, county of Wayne, State of Michigan, have invented certain new and useful Improvements in Disk Wheels, of which the following is a specification.

This invention relates to improvements in disk wheels.

10 The object of the invention is to provide a disk wheel structure which will be simple and inexpensive to manufacture and yet very strong in use.

15 A further object is to provide a disk wheel structure in which the web of the wheel is made up of sections with an effective and simple joint therebetween.

20 Objects pertaining to details and economies of construction and operation will definitely appear from the detailed description to follow.

25 I accomplish the objects of my invention by the devices and means described in the following specification. The invention is clearly defined and pointed out in the claims.

30 A structure which is a preferred embodiment of my invention is fully illustrated in the accompanying drawings, forming a part of this application, in which:

35 Fig. I is an outside elevation view of a wheel embodying the features of my invention, with the rim demounted.

Fig. II is an enlarged detail sectional view of such wheel taken on line 2—2 of 40 Fig. I.

Fig. III is an enlarged detail sectional view of the seamed retaining rib taken on line 3—3 of Fig. I.

Fig. IV is a detail perspective view of one 45 of the sections or segments of the web of the wheel.

Fig. V is an enlarged detail elevation view of the inner portion of one of the wheels showing the arrangement of the joint member and its connection to the rim.

Fig. VI is a detail sectional view taken 50 on line 6—6 of Fig. V, showing the construction of the seamed joint and the connection to the fixed rim.

Fig. VII is a detail sectional view similar 55 to Fig. II, of a modified form of the wheel in which the disk is conformed into double concavo-convex or concentric corrugation formation to increase the strength and improve the appearance.

Fig. VIII is a detail perspective view of

one of the sections of the web of this modification.

In the drawing similar numerals of reference refer to similar parts throughout the 60 several views and the sectional views are taken looking in the direction of the little arrows at the ends of the section lines.

The parts of the drawing will be considered by their numbers. 1 is the hub having a fixed flange 2 and a detachable flange 3 held upon the web 5 of the wheel by clamping bolts 4. Filler plates 51, 52 are interposed each side of the web 5 to give body 65 at the hub center. The web 5 is made up 70 of angular sections 6,—see Fig. IV, the edges of which are joined together by the seamed sheet metal joint member 7 which is folded upon itself at 8, 8 and folded outwardly at 9, 9 and inserted between the said members 75 engaging the edges of the section 6, as clearly appears in Figs. III and V. When the wheel has been thus assembled together, the fixed rim 11 is put in place and riveted or otherwise secured to the flanged outer 80 edge of the web 5, as seen at 61, the same being secured in place by rivets 62.

The only difference between the structure of Fig. II and Fig. VII is a concentric corrugating or double concavo convex curving 85 of the web of the wheel as seen at 5' and 6' in Fig. VIII. The joint member 7 is suitably conformed thereto. The special form shown in Fig. VII accommodates the valve stem 13 so that it is accessible from the outside of the wheel.

In Fig. VII I show a fragment 12 of the demountable rim and the position of the valve stem 13.

In the manufacture of the wheel, it will be 95 seen that the web, being made up of the sections 6, can be readily made of sheet metal in a stamping press and the flange 61 turned at the outer end thereof and the inner end suitably perforated to accommodate the flange bolt 4. The finishing seamed joint rib 7 is then inserted in place and the entire wheel conformed and the flanged outer end riveted to the fixed rim of the wheel, the same being of suitable form to 100 accommodate the demountable rim. The fixed rim might be suitably flanged to receive a tire of the clincher type. The form of the fixed rim is not material to my invention.

I desire to claim the invention broadly 110 and in its specific form illustrated, as pointed out in the appended claims.

Having thus described my invention, what I claim as new and desire to secure by Letters Patent, is:

1. In a disk wheel, the combination of a hub with suitable flanges, a web for the wheel made up of sheet metal sections, seamed joint members therebetween formed of sheet metal with an inturned and out-turned portion to form grooves at each side to retain and engage the edges of the said sections, filler disks between the hub flanges to embrace the inner ends of the said wheel, and a fixed rim riveted to the outer flange of the said wheel, all substantially as described.
- 10 2. In a disk wheel, the combination of a hub with suitable flanges, a web for the wheel made up of sheet metal sections, seamed joint members therebetween formed of sheet metal with an inturned and out-turned portion to form
- 15

turned portion to form grooves at each side 20 to retain and engage the edges of the said sections, and a fixed rim secured to the outer flange of the said wheel, all substantially as described.

3. In a disk wheel, the combination of a hub with suitable flanges, a web for the wheel made up of concentrically corrugated sheet metal sections, seamed joint members therebetween formed of sheet metal with an inturned and out-turned portion to form 25 grooves at each side to retain and engage the edges of the said sections, and a fixed rim secured to the outer flange of the said wheel, all substantially as described.

In witness whereof, I have hereunto set 30 my hand and seal.

WILLIAM A. GIBSON. [L.S.]
